(57) **CLAIM**

The ornamental design for a piano with skyline design, as shown and described.

DESCRIPTION

FIG. 1 is a front, right-side perspective view of the piano with the skyline design, with a lid of the piano in an open position.

FIG. 2 is another front, right-side perspective view thereof.

FIG. 3 is a right-side view thereof.

FIG. 4 is a rear, right-side perspective view thereof.

FIG. 5 is another rear, right-side perspective view thereof.

FIG. 6 is a rear view thereof.

FIG. 7 is a rear, left-side perspective view of the piano with the skyline design, with the lid of the piano in a closed position.

FIG. 8 is a rear, left-side perspective view of the piano with the skyline design, with the lid of the piano in the open position.

FIG. 9 is a left-side view thereof; and,

FIG. 10 is an enlarged, partial, front, right-side perspective view thereof.

Features of the piano with the skyline design that are shown bounded by broken lines in FIGS. 1, 2, 4, and 5 are disclaimed and form no part of the design to be patented.

1 Claim, 10 Drawing Sheets
